B. G. POHLMANN

TELEPHONE REPEATER SYSTEM

Filed Sept. 11, 1924

FIG. 2

Inventor

Bruno Berhard Pohmann

By Knight Bryan
attorney

UNITED STATES PATENT OFFICE.

BRUNO GERHARD POHLMANN, OF SIEMENSSTADT, NEAR BERLIN, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

TELEPHONE REPEATER SYSTEM.

Application filed September 11, 1924, Serial No. 737,119, and in Germany September 14, 1923.

My invention relates to improvements in telephone repeater systems.

Repeater connections are already known in which the selectivity of the transmitters is reduced by the connection of additional damping means for the purpose of obtaining as uniform a repetition as possible of all the frequencies necessary for the conversation.

Such additional damping means may consist of a shunt impedance comprising in series connection ohmic resistance, inductance and capacity.

In the drawing affixed to this specification and forming part thereof shows:—

Fig. 1, curves explaining the manner of operation of the improved repeater system.

Fig. 2, a diagram of the improved repeater system.

Referring to Fig. 1, A is the amplification curve and B the damping curve of the line. If, for instance, the amplification should just neutralize the damping of the line, the amplification curve is so chosen that it intersects the damping curve in two points which are located outside the frequency range necessary for the clearness of articulation. One of these points is located lower than the lowest frequency the good transmission of which is desired and the other higher than the highest frequency to be satisfactorily transmitted.

If the ohmic resistance K according to Fig. 2 alone is connected in parallel with one of the incoming or outgoing transmitter coils, for instance parallel with the secondary coil of the incoming transmitter the amplification curve is flattened and lowered as a whole so that, for instance, it takes up the position 2—2 in which it runs along the damping curve over a short range only. If on the other hand the entire shunt impedance according to Fig. 2 of the drawing, which consists of the series connection: ohmic resistance K, inductance L and capacity C is connected up and if the inductance and the capacity C are so dimensioned that resonance exists at that frequency for which the greatest reduction of the amplification is desired which generally will be the case with the frequency located in the middle between the limiting frequencies then the

damping resistance for this frequency is smallest while it increases on the other hand for the higher and lower frequencies. A curve of about the shape of the curve 3—3, Fig. 1, is then obtained. The ascent of the higher frequencies is, however, not yet sufficient.

My invention consists in connecting a condenser C' in parallel with the inductance L as shown in Fig. 2 which condenser is so dimensioned that it is in resonance with the inductance L for frequencies in the neighborhood of the highest frequency in the necessary speech range, or higher, so that for this frequency the resistance is very high; that means its damping action is very small.

An amplification curve corresponding with the curve 4—4, Fig. 1, is then obtained which within the desired frequency range agrees well with the damping curve.

As appears from the above explanations given by way of example an essential characteristic is that the shunt resistance is a resonance structure with a plurality of resonance places. Consequently the same effects may also be attained if another structure consisting of inductivity, capacity and resistance with two or more resonance places is employed. It would, for instance be possible to employ two different cross-sections which consist of a series connection of resistance, inductance and capacity.

As a matter of course it is possible to produce the effect produced at one place of the repeater upon the amplification curve by one of the above resonance structures also by a plurality of structures connected at various places.

What I claim as my invention and desire to secure by Letters Patent is:—

In a transmission system the loss characteristic of which varies non-linearly with frequency in the band of transmitted frequencies, an amplifying repeater and means associated therewith for compensating for said non-linear characteristic comprising a circuit connected in shunt relation to said system and comprising resistance, inductance and capacity elements in series with one another and proportioned to possess series resonance at a point intermediate the extreme frequencies in the transmitted band

whereby components of frequencies both lower and higher than the resonance frequency are absorbed from the system to a less extent than components at or near the 5 resonance frequency, and means associated with said shunt circuit tending to make it anti-resonant at a frequency at least as high as the highest frequency portion of the transmitted band whereby the absorption by said shunt circuit as the higher frequencies 10 are approached gradually becomes less.

In testimony whereof I affix my signature.

BRUNO GERHARD POHLMANN.
